ILLINOIS

LOCK

Application filed February 23, 1929. Serial No. 341,911.

This invention has to do with locks, and is particularly concerned with door locks of the type in which a single bolt is made to serve both as a latch bolt and as a dead bolt.

5 The principal object of the invention is to provide a novel door lock which is easy to install and operate, cannot be forced, and is inexpensive to manufacture.

Other objects and advantages of the invention will be apparent to those skilled in the art upon a full understanding of the construction, arrangement and operation of the lock.

One embodiment of the invention is presented herein for the purpose of exemplification, but it will of course be understood that the invention is capable of being embodied in other structurally modified forms coming equally within the comprehensive scope of the appended claims.

In the accompanying drawings:

Fig. 1 is a side elevation of the lock, as viewed from the inside of the door to which applied;

25 Fig. 2 is another side elevation of the lock, as viewed from the outside of the door;

Fig. 3 is a plan view of the lock;

Fig. 4 is a longitudinal section through the casing of the lock, showing the bolt in 30 its normal projected position;

Fig. 5 is a corresponding section, showing the bolt in its retracted position;

35 Fig. 6 is a somewhat similar section passing between the two laterally separable sections of the bolt, showing the locking dogs retracted within the bolt;

Fig. 7 is a corresponding view, showing the locking dogs projected with respect to the bolt;

40 Fig. 8 is a diametric section through both the inside and outside lock-operating mechanisms, taken on the line 8-8 of Fig. 2;

Fig. 9 is a fragmentary section corresponding to the right-hand portion of Fig. 8, showing a key inserted in the lock cylinder in the outside knob;

45 Fig. 10 is transverse section through the key-operated clutch, taken on the line 10-10 of Fig. 9; and

Fig. 11 is a longitudinal horizontal section through the bolt.

The lock shown in the drawings includes a tubular casing 10 in which a bolt 11 is 55 slidably mounted. The bolt is normally caused to project from the front end of the casing by the action of coil springs 12, which springs fit into recesses 13 formed in the opposite sides of the bolt and bear against blocks 14 which are secured to the inside 60 wall of the casing by screws 15.

The bolt may be retracted against the action of the springs by turning either an inside knob 16 or an outside knob 17. The inner end 18 of the knob 16 is journaled in a 65 bore 19 in a bracket 20 which fits about one side of the casing over an opening 21 therein, while the inner end 22 of the knob 17 is journaled within a bore 23 in a bracket 24 which fits about the other side of the casing over an opening 25 therein. The brackets 20 and 24 are clamped tightly about the casing by screws 26 positioned above and below the casing.

The knobs 16 and 17 are held against outward axial movement in the tubular portions of the brackets by means of rings 27 which fit over the inner ends of the knobs inside of the brackets and are held in position by transfixing pins 28. The inner ends of the knobs telescope over hub portions 29 on cam 70 members 30, and the cam members are caused to rotate with the knobs by eccentrically positioned pins 31 which project from the cam members into sockets (not shown) in the inner ends of the knobs. The cam members 30 75

are positioned against flattened surfaces on opposite sides of the bolt 11, and are each provided with two cams 32 and 33 which are adapted to engage respectively with shoulders 34 and 35 formed on the bolt adjacent the rear 80 end thereof. When either the knob 16 or knob 17 is turned a portion of a revolution, one of the cams on the cam member connected with that knob will bear against the opposed shoulder on the bolt and cause the bolt to 85

shift rearwardly in the casing against the yielding resistance of the springs from the position shown in Fig. 4 to that shown in Fig. 5.

The bolt contains a pair of locking dogs 100

36 and a slide 37 to which the dogs are connected by links 38. The dogs are preferably curved, as shown in Fig. 6, and are positioned in correspondingly shaped guideways 39. 5 When the slide 37 is shifted toward the front end of the bolt, the front ends of the dogs are projected from the same, as shown in Fig. 7, and, when the slide is shifted rearwardly in the bolt, the dogs are retracted, as 10 shown in Fig. 6. The bolt is preferably made in two laterally separable parts 40 and 41. The part 41 is relatively thick, and is hollowed out to accommodate the dogs 36, the slide 37 and the links 38, while the part 40 15 is relatively thin, and forms in effect a cover plate for the part 41, to which it is secured by screws 42. The rear portions of the parts 40 and 41 are provided with longitudinally elongated openings through which a stem 43 for 20 operating the dogs 36 passes.

The stem 43 is coaxial with the bolt-retracting knobs 16 and 17 but operates independently thereof to project or retract the dogs 36 with respect to the bolt when the bolt is in its 25 normal projected position. The stem is secured at one end to a head 44 which is journaled within the inner end 22 of the knob 17 and extends loosely through the hub portions 29 of the cam members 30. Throughout 30 the greater portion of its length the stem is flattened at opposite sides to make it of non-circular cross-section, and a cam member 45 having a bore of corresponding cross-section is non-rotatably mounted on the stem within 35 the bolt between the cam members 30. When the cam member 45 is rotated by the stem 43 in the direction indicated by the curved arrow in Fig. 6, a cam 46 on the cam member moves into engagement with a shoulder 47 on the slide 37, depresses the adjacent end 48 of a pivoted arm 49 whereby to lift the other notched end 50 of such arm out of interlocked engagement with a cross pin 51 in the bolt, and shifts the slide 37 forwardly within the 40 bolt, thus projecting the front ends of the locking dogs from the front end of the bolt into the position shown in Fig. 7. When the cam member 45 reaches the position shown in Fig. 7, the cam 46 allows the end 48 of the 45 arm 49 to swing upwardly, whereupon the end 50 of the arm in consequence moves downwardly under the action of a spring 52 into a position wherein notches in the lower portion of that end of the arm come into interlocked engagement with the pin 51 and another 53, thereby locking the slide 37 against rearward movement. During the above described forward movement of the slide within the bolt, a small catch 54 which is pivoted 55 to the bolt at 55 is caused by a lug 56 on the slide to swing from the position shown in Fig. 6 to the position shown in Fig. 7, in which latter position, a projection 57 on one end of the catch is forced upwardly into an 60 opening 58 in the casing, thereby holding 65

the projected bolt against retraction as long as the locking dogs remain projected. When the cam member 45 is turned in the other direction, the movement of the mechanism within the bolt is reversed. The cam 46 first rocks 70 the arm 49 to lift the notched end of the same out of engagement with the pins, and then engages with a shoulder 59 on the slide and shifts the slide rearwardly, which movement of the slide causes the catch 54 to disengage 75 from the casing.

The stem 43 may be turned either from the inside by a thumb piece 60, or from the outside by a key 61 operating in a lock cylinder 62. The thumb piece 60 is arranged concentrically of the inner knob 16 and is provided with an inwardly extending portion 63 which is journaled within the inner end 18 of the knob 16 and contains a non-circular recess 64 in which the flattened portion of the stem 43 fits in non-rotatable engagement therewith. When the thumb piece 60 is turned, it will turn the stem 43, which in turn will cause the cam member 45 to shift the slide 37 forwardly or rearwardly within the bolt, thereby projecting or retracting the dogs 36, depending upon the direction in which the thumb piece is turned. When the key 61 is inserted in the keyway in the lock cylinder 62 far enough to release the tumblers (not shown) in the cylinder, the inner tip of the key will engage with a floating head 65 which is non-rotatably associated with the key-operated portion of the cylinder and will force the same toward the stem-carrying head 44 against the 90 yielding resistance of an interposed coil spring 66, resulting in an arc-shaped lug 67 on the inner face of the head 65 being moved into lapped relation with a coacting clutch stud 68 on the outer face of the head 44. 95 When the key is then turned in the cylinder, the lug 67, after a certain amount of free movement, will engage with the stud 68 and will turn the head 44, thereby rotating the cam member 45 and shifting the slide 37 to 100 either project or retract the dogs 36 with respect to the bolt.

In order to maintain the cam member 45 with the cam 46 thereon normally in the position shown in Fig. 6, a pair of small wire 115 springs 69 are positioned in the longitudinally elongated openings in the sides of the bolt in spring pressed engagement with flattened surfaces 70 on otherwise circular axially-extending hub portions of the cam member 45. When a positive force is applied through either the thumb piece 60 or the key 61, to rotate the cam member 45, the springs 69 will yield and permit such rotation, but at all other times the springs will tend to prevent the cam member 45 from inadvertently leaving the neutral position of the same shown in Fig. 6. Thin spacing washers 71 may be inserted between the cam member 45 and the 120

cam members 30 to prevent the rotation of the latter from affecting the former.

The peculiar undercut shaping of the cams 32 and 33 on the cam members 30, and the complementary oblique shaping of the shoulders 34 and 35 on which such cams ride, allow the bolt to be fully retracted with a small turn of either one of the knobs, and prevent the cams from being moved into dead center positions wherein the action of the springs 12 would be rendered ineffective.

It might be desirable to have, in a lock of the type under consideration, means for preventing the locking dogs 36 from being retracted by the outside key 61 after such dogs have been projected by the inside thumb piece 60. This may be accomplished by providing an angularly disposed groove 72 in the inwardly extending portion 63 of the thumb piece and having a stud 73 carried either by a portion of the knob or by a non-rotatable extension of the bracket 20 project into the groove, whereby to cause the thumb piece, when it is turned to project the dogs, to move inwardly at the same time and force the head 44 against the head 65. This will prevent the head 65 from being shifted inwardly by the tip of the key, with the result that the key cannot be inserted in the lock cylinder far enough to release the tumblers therein.

Any or all of the various lock parts above described obviously may be made up in any number of sections desired, in order to facilitate manufacture and assemblage. The escutcheon plates ordinarily employed with a lock of the type here under consideration, may be positioned against the sides of the door in proper relation to the lock by passing the screws used to tie the plates together through aligning notches 74 formed in the upper and lower portions of the brackets 20.

I claim:

1. In a door lock, a spring-projected bolt, inside and outside means operable independently of each other to retract the bolt, a supplemental locking member carried by the bolt, and inside and outside means operable independently of each other to project said member with respect to the bolt.

2. In a door lock, a spring-projected bolt, means for retracting the bolt, a supplemental locking member carried by the bolt, outside key-controlled means for projecting said member with respect to the bolt, and inside means operable independently of said key-controlled means to similarly project said member.

3. In a door lock, a spring-projected bolt, inside and outside means operable independently of each other to retract the bolt, a supplemental locking member carried by the bolt, outside key-controlled means for projecting said member with respect to the bolt, inside means operable independently of said key-controlled means to similarly project

said member, and means for preventing use of the key-controlled means to retract the projected member after the same has been projected by the inside means.

4. In a door lock, a bolt having a transverse opening therein, a supplemental locking member carried by the bolt, means extending into said opening for moving the bolt, and separate independently operable means extending into said opening concentric association with the first mentioned means for moving said member relative to the bolt.

5. In a door lock, a tubular casing forming a guideway, a bolt supported in the guideway in closely fitted sliding association therewith, spring means for normally projecting one end of the bolt from the casing, inside and outside means operable independently of each other to retract the bolt into the casing against the action of said spring means, a supplemental locking member carried by the bolt, inside and outside means operable independently of each other to project said member from the projected portion of the bolt, and means coacting with the guideway and the bolt to prevent retraction of the latter as long as said member is in a projected position.

6. In a door lock, a tubular casing, a bolt slidably mounted in the casing, spring means for normally projecting one end of the bolt from the casing, an inside knob at one side of the casing rotatable to retract the bolt against the action of said spring means, an outside knob on the other side of the casing rotatable to similarly retract the bolt, a supplemental locking member slidably mounted in the bolt, an inside finger piece movable to project said member from the projected portion of the bolt, an outside key rotatable to similarly project said member, means for preventing retraction of the bolt as long as said member is in a projected position, and means for preventing retraction of said member by the key after said member has been projected by the finger piece.

7. In a door lock, a tubular casing, a bolt slidably mounted in the casing, spring means for normally projecting one end of the bolt from the casing, an inside knob at one side of the casing rotatable to retract the bolt against the action of said spring means, an outside knob at the other side of the casing rotatable to similarly retract the bolt, a pair of dogs slidably mounted in the bolt, an inside finger piece movable to project the dogs from the projected portion of the bolt in different directions, an outside key rotatable to similarly project the dogs, and means for preventing retraction of the bolt as long as the dogs are in projected positions.

8. In a door lock, a tubular casing, a bolt slidably mounted in the casing, spring means for normally projecting one end of the bolt

from the casing, an inside knob at one side of the casing rotatable to retract the bolt against the action of said spring means, an outside knob at the other side of the casing rotatable to similarly retract the bolt, a pair of hooked dogs slidably mounted in the bolt, an inside finger piece rotatable to project the dogs from the projected portion of the bolt in diverging directions, an outside key rotatable to similarly project the dogs, and means for preventing retraction of the bolt as long as the dogs are in projected positions.

9. In a door lock, a casing having an elongated tubular portion, a bolt supported in the tubular portion of the casing in closely fitted sliding association therewith, a supplemental locking member carried by the bolt for projection from the end thereof, means for projecting the end of the bolt from the casing, and independently operable means telescopically associated with said last mentioned means for projecting the supplemental locking member from the end of the bolt after the latter has been projected from the casing, one of said two last mentioned means being journaled in the other and the latter being journaled in the casing on an axis passing transversely through the bolt.

10. In a door lock, a casing having an elongated tubular portion, a bolt supported in the tubular portion of the casing in closely fitted sliding association therewith, a supplemental locking member carried by the bolt for projection from the end thereof, means for projecting the end of the bolt from the casing, and independently operable means for projecting the supplemental locking member from the end of the bolt after the latter has been projected from the casing, said two last mentioned means extending perpendicularly of the bolt into an aperture formed in the latter intermediate the ends thereof.

In testimony whereof I have hereunto sub-
45 scribed my name.

LOUIS L. BRESLER.
